SHOE CLAMP

Wilbur E. Landers, Chicago, Ill.

Application June 26, 1941, Serial No. 399,920

3 Claims. (Cl. 15—267)

This invention relates to a shoe shining cabinet, the general object of the invention being to provide a cabinet having a number of compartments therein for receiving various articles for shining or polishing and cleaning shoes with means carried by the cabinet for holding shoes in a position where they can be readily cleaned and polished, the shoe holding means including lasts for different sizes of shoes, the last being removably supported on an upright extending from the top of the cabinet adjacent one end thereof with a spring member for engaging the heel of the shoe to hold the parts firmly in position while they are being cleaned and polished with another upright member for holding different sizes of shoes while the same are being cleaned and polished.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a side elevational view of the cabinet with parts broken away and showing the two shoe holding members.

Figure 2 is a view looking toward the outer side of that shoe holding member which is removably attached to an end of the cabinet.

Figure 3 is a section on the line 3—3 of Figure 2.

Figure 4 is a section on the line 4—4 of Figure 1.

Figure 5 is a section on the line 5—5 of Figure 3.

Figure 6 is a top plan view of the shoe holding last.

Figure 7 is a view of the bracket for holding the shoe holding member, shown in Figure 2, to an end of the cabinet.

In these views the cabinet is shown at A and it is provided with a high part a at one end thereof and, the cabinet is divided into a plurality of compartments B for receiving various articles used in cleaning and polishing shoes, one of these compartments being located in the part a and the compartments are closed by doors b. That end portion of the cabinet opposite the end having the high part a thereon is open excepting for a flange 1 which extends over an end portion of the top of this part of the cabinet and a bracket 2 is fastened to this part 1 by fastening means passing through holes 3 in the bracket into the part 1. This bracket is provided with the spaced apart raised portions 4 as shown in

dotted lines in Figure 2 and the outer end edges of these raised portions are notched as shown at 5, see Figure 7. A vertically arranged shoe supporting member C is detachably connected at its lower end to the bracket by having the headed lugs 6 extending from its bottom portion for engaging the notches 5, these lugs depending downwardly from the lower end of the member C. This member C is of substantially T-shape in cross section to provide a web 7 and a flat part 8. This flat part is provided with a lower reduced portion 8' and a tapered part 8'' which tapers upwardly from the upper end of the reduced part 8' the web 7 is provided with a longitudinally extending slot 9 and plates or wings 10 extend outwardly from both sides of the web and under the reduced part and are spaced outwardly from the slot 9 as shown in Figure 3. A screw shaft 11 passes through the slot and has its central portion yieldingly held to the web 7 by means of the stabilizing plates 12, each plate being engaged by a wave spring washer 13 which, in turn, is engaged by a flat washer 14 and a slotted washer 15 engaging each flat washer and holds the part with the plates yieldingly engaging the web so that the shaft can be adjusted in the slot 9. The shaft is threaded on those portions which extend from the web, one portion being reversely threaded relative to the other portion and nuts 16 engage the threaded portions and an upright member 17 is connected to the outer face of each nut and has a heel engaging clamp 18 at its upper end, the lower end of each member 17 sliding on the plate 10. A crank handle 19 is connected to one end of the shaft 11 so that the same can be rotated to move the members 17 and their clamps 18 toward or away from each other. These clamps 18 are adapted to engage the sides of a heel of a shoe placed on the device C. Projections 21 extend outwardly from both faces of the web 7 and under an intermediate part of the portion 8'', these projections having their ends converging downwardly and a slotted spring member 22 is fastened to each of the projections by a thumb screw 23 which passes through the slot 24 of the spring. The upper end of the spring is bent slightly inwardly to provide a flange 25 and this flange is preferably covered with rubber or the like. A U-shaped member 26 has its bight provided with a hole for receiving the thumb screw 23 with the limbs of the U-shaped member extending over the side edges of the spring 22 and of each projection 21 with the bight extending across a portion of the slotted part of the spring, this member acting as a spring guard and stabilizer. By adjusting the spring 22 by means of its thumb nut 23 the flange 25 can be adjusted toward or away

from the outer face of the member 8" so as to fit shoe soles of different thicknesses and widths. As will be understood the shoe to be held by the device is moved downwardly on the flat part 8" until the side edges of the sole adjacent the instep are engaged by the flanges 25 of the springs 22 and then the shaft 11 is adjusted in the slot 9 to place the clamps 18 in proper position to fit the sides of the heel of the shoe and then the shaft is turned to cause the flange to move inwardly to grip the sides of the heel. Thus this device C will hold shoes of different sizes and this device when formed as shown in Figure 2 will hold the shoe with practically all parts of the device out of the way when the shoe is being cleaned or polished.

An upright 27 is attached to the base of the cabinet adjacent the part 1 and has its upper end passing through the top of the cabinet with this upper end bent at right angles as shown at 28. A shoe last 29 has a socket member 30 fastened in the heel portion thereof and this socket member has a non-circular socket 31 therein for receiving the non-circular end of the part 28. The parts being connected together by a screw 32 passing through a threaded hole in the socket member. This last is provided with the heel part 33, see Figure 6, and the two sections 34 forming the toe part, the two sections being hinged to the heel part as shown at 35 and the two sections are pressed apart by the spring 36. Thus this last will fit shoes of different sizes so it is not necessary to provide a last for each size of shoe.

An upright guide member 38 is connected to the bottom of the cabinet by a spring hinge 39, this member being provided with the flanges 40 and an elongated member 41 is slidably arranged in the member 38 having its side edges fitting in the space formed by the flanges. The member 38 has a vertical or longitudinal extending slot 42 therein and a lug 43 is fastened to a part of the member 41 passing through the slot and terminates in a collar 44 which slides on a rod 45 carried by the bent parts or brackets 46 extending from the member 38. A spring 47 is located on the rod and tends to hold the collar 44 against the lower brackets 46. A hook 48 is formed on the upper end of the member 41 and a handle 49 is also attached to the upper end of this spring 41.

A spring clamp 50 is located in the cabinet, as shown in Figure 3, and a short tube 51 encloses the upper portion of the spring 47 and a portion of this tube will fit in the clamp 50 when the member 38 is swung to the right in Figure 3 so as to hold the heel engaging assembly out of the way when a shoe is being placed on the last 29.

After a shoe has been placed on the last 29 the member 38 and the parts attached thereto is pulled from the clamp so that the spring will raise the member 38 and the member 41 is raised by a pull upon the handle 49. This raising of the member 41 will tension the spring so that when the hook 48 is placed over the inner edge of the heel of the shoe the spring will cause the hook to remain in firm engagement with the heel and thus the shoe is firmly held on the last so that it can be cleaned and polished. When it is desired to remove the shoe from the last the handle 49 is grasped and the member 41 pulled upwardly and at the same time the member 38 is

pushed downwardly into the clamp 50 and then the shoe can be removed from the last.

Thus it will be seen that I have provided a cabinet for containing articles used in cleaning and polishing shoes with two members for holding the shoes while the same are being cleaned and polished, with these parts so arranged that they will not interfere with the cleaning and polishing of the shoes, and the device is so formed that shoes of different sizes can be placed thereon. It will, of course, be understood that different sizes of lasts 29 can be used say, one for children shoes, another for ladies shoes and still another for men shoes.

15 Preferably the nuts 16 are formed by punching a hole in each member 17 by pressing the metal inwardly to form the nut and then the nuts are threaded one with right hand threads and the other with left hand threads.

20 It is thought from the foregoing description that the advantages and novel features of the invention will be readily apparent.

25 It is to be understood that changes may be made in the construction and in the combination and arrangement of the several parts provided that such changes fall within the scope of the appended claims.

Having described the invention, what is claimed as new is:

30 1. In a device of the class described, a shoe support including, an upright member having a flat part against which a sole of a shoe rests, heel engaging clamps carried by the upright member, screw means for adjusting the clamps 35 for engaging the sides of a heel, said clamps having a flat lower edge, a plate slidably engaged by said lower edge of the clamp to retain the upper edge of the clamp in an upright position and clamps carried by the upright member for engaging side portions of the sole of a shoe.

2. In a device of the class described, a shoe support including, an upright member having a flat part against which a sole of a shoe rests, heel 45 engaging clamps carried by the upright member, screw means for adjusting the clamps for engaging the sides of a heel, said clamps having a flat lower edge, a plate slidably engaged by said lower edge of the clamp to retain the upper edge 50 of the clamp in an upright position and clamps carried by the upright member for engaging side portions of the sole of a shoe, and means for adjusting the last-mentioned clamps to suit soles of different thicknesses.

3. In a device of the class described, a shoe support including an upright member having a flat part against which the sole and heel of a shoe is adapted to rest, heel engaging clamps carried by the upright member, screw means for adjusting the clamps toward and away from each other to cause the clamps to engage the sides of a shoe heel, said clamps having a flat lower edge, a plate slidably engaged by said lower edge of the clamp to retain the upper edge of the clamp in an upright position means for adjusting the clamps longitudinally on the upright member, a pair of clamps on an intermediate part of the upright member for engaging the side edges of the sole of a shoe, and means for adjusting the last-mentioned clamps to suit soles of different thicknesses.

WILBUR E. LANDERS.
